UNITED STATES PATENT OFFICE.

WILLIAM ILE, OF TORONTO, ONTARIO, CANADA,

ELECTRIC-LAMP-SOCKET SHELL.

1,241,851.

Specification of Letters Patent.

Patented Oct. 2, 1917.

Application filed February 19, 1917. Serial No. 149,459.

To all whom it may concern:

Be it known that I, WILLIAM ILE, a subject of the King of Great Britain, and resident of the city of Toronto, county of York, Province of Ontario, in the Dominion of Canada, have invented certain new and useful Improvements in Electric-Lamp-Socket Shells, described in the following specification and illustrated in the accompanying drawings, that form part of the same.

The objects of the invention are, to eliminate the dangers of short circuits in electric lamps due to the accidental loosening of the socket shell and to provide a shell in which the body portion may be securely locked to the cap and which may be easily and quickly released and removed.

The principal feature of the invention consists in the novel construction of the shell whereby laterally arranged tongues are formed on one of the shell members and are adapted to interlock with projections formed on the other member, and whereby the body of the shell is slit to engage a projecting portion of the cap to lock the members.

In the drawings, Figure 1 is a perspective view of a shell constructed in accordance with this invention showing the cap removed from the body portion.

Fig. 2 is an enlarged perspective detail partly broken away illustrating the coöperative interlocking features.

Fig. 3 is an enlarged perspective detail of a portion of the cap and body showing the tongue member entering the recess formed by one of the loops.

Fig. 4 is an enlarged vertical sectional view through the interlocking members.

Lamp socket shells of numerous kinds have been manufactured in which one of the members is provided with protuberances which are adapted to enter corresponding holes or recesses in the other member and these are sprung into place but such constructions are found to be very unreliable particularly when the members have been disconnected a few times with the result that the body portion of the shell pulls away from the cap and frequently results in the short circuiting of the wiring or terminals which is both dangerous and inconvenient.

The construction described in the present application has been devised with a view to definitely locking the shell and cap together and to this end the shell 1 is formed with the

notches 2 in the upper edge. These notches are so shaped as to form in each a tongue 3 which extends laterally from one side thereof. The end of the tongue is spaced from the opposite side wall 4 of the notch a distance sufficient to allow of the passing of a loop member 5 formed in the rim of the cap 6. The loops are preferably formed by indenting the metal of the rim of the cap and the metal is sheared and stretched inwardly a sufficient distance to provide openings 7 through which the tongue members 3 may pass.

The notches 2 in the shell are spaced equidistant as are the loops 5 in the cap and these are arranged to coincide. The cap here shown is provided with four loops and the shell with three notches to register with the loops and in place of a fourth notch the shell is formed with a longitudinal slit 8 which may be sufficiently wide to receive the shank of the key of the socket or in keyless sockets the slit is only slightly wider than the width of the loops 5.

The edge of the slit 8 is so arranged in relation to the notches 2 that when the cap is placed upon the top of the body portion so that several loops are in alinement with the space between the ends of the tongues and the sides of the notches, one of the loops 8 will engage the outer face of the shell close to the slit and as the cap is forced into position the metal of the shell springs inwardly.

When the cap has been pushed to its downward limit upon the shell it is then rotated thereby causing the tongues 3 to pass through the openings 7 and across the loops 5, the ends of the tongues passing completely across the loops and interlocking with the metal at each side thereof. As the cap is thus turned the loop adjacent to the slit 8 drops into the slit as the loops are brought into contact with the sides of the notches forming their locking limitation and the metal of the shell springs into one side of the loop, thereby locking the cap from accidental rotation.

When the cap is thus held from rotation the tongues extending completely through the loops form an absolute lock between the body of the shell and the cap so that it will be impossible to pull the two apart unless of course sufficient force is exerted to either shear off the tongues or break through the loops which is practically impossible under 110

any conditions that would arise in such devices.

When it is desired to separate the body of the shell from the cap it is merely necessary 5 to spring the metal inwardly from locking engagement with the loop at the slit and the cap may then be turned quite freely and when turned back until the loops engage the side walls 4 of the notches the cap will 10 slip off without any strain being placed upon it.

A socket shell such as described goes together very easily, no portion of either the body or the cap is placed under abnormal 15 strain and in separating the parts no unnecessary strain is placed upon any portion as the action is merely a simple and unobstructed release.

The device as herein shown and described 20 in detail shows the tongue members passing through a loop but it must be understood that the tongue may engage an inward projection other than of loop form.

What I claim as my invention is:—

25 1. An electric lamp socket shell, comprising, a separable body and cap, one of said members having laterally arranged tongues and the other having loops adapted to receive and interlock with said tongues, the 30 member having the tongues being slotted

inwardly from the edge to receive one of said loops on the interlocking of the tongues with the remaining loops.

2. An electric lamp socket shell, comprising a cap having inwardly projecting loops 35 formed in the flange and spaced equidistant, and a body formed with a plurality of notches in the upper edge, certain of said notches being spaced to correspond with the loops on the cap and having laterally arranged tongues adapted to extend through said loops upon a partial rotation of the cap, and other of said notches being spaced to receive a corresponding loop upon the rotation of the cap and arranged to engage 40 the edges of the loop to hold the cap from rotation.

3. An electric lamp socket shell, comprising, a body formed with a plurality of notches in the upper edge and laterally arranged tongues at one side of said notches, said body also having a longitudinal slit 50 in the upper edge, and a cap having indentations formed in the rim and forming loops to engage said tongues, one of said loops fitting into said slit when the tongues are arranged in engagement with the loops to 55 lock said tongues and loops together.

WILLIAM ILE.
